United States Patent

Des. 239,998
Patented May 25, 1976

239,998

PICTURE FRAME

William Burton Barber, Sr., 2911 Monroe Place,
Falls Church, Va. 22042

Filed Mar. 21, 1974, Ser. No. 453,540

Term of patent 7 years

Int. Cl. D6—07

U.S. Cl. D6—242

Fig-1

Fig-2

Fig-3

Fig-4

Fig-5

FIG. 1 is a front, top and right side perspective view of a picture frame showing my new design;

FIG. 2 is a front elevational view;

FIG. 3 is a left side elevational view;

FIG. 4 is a bottom plan view; and

FIG. 5 is a front, bottom and left side perspective view. The rear of the picture frame is plain and unornamented.

I claim:

The ornamental design for a picture frame, substantially as shown and described.
